UNITED STATES PATENT OFFICE

FRANK L. BAMFORD, OF DETROIT, MICHIGAN, ASSIGNOR TO C. M. HALL LAMP COMPANY, OF DETROIT, MICHIGAN, A CORPORATION OF MICHIGAN

LAMP

Application filed January 23, 1928. Serial No. 248,768.

This invention relates to adjusting mechanisms and has particular reference to an adjusting mechanism for the lamp bulb of a lamp.

An object of this invention is to provide an adjusting mechanism having means for compensating for variations in the alignment of different portions thereof.

A still further object of this invention is to provide an adjusting mechanism, having the means aforesaid, which mechanism will be simple in construction and yet thoroughly efficient in operation.

Other objects and advantages of this invention will become apparent as the following description proceeds, particularly when reference is had to the accompanying drawings wherein,

Figure 1 is a vertical sectional view through a lamp, having adjusting mechanism constructed in accordance with this invention applied thereto;

Figure 2 is a fragmentary horizontal sectional view through the structure shown in Figure 1;

Figure 3 is a detailed perspective view of the elements of the adjusting mechanism showing the same in the order of and prior to their assembly, and

Figure 4 is a side elevational view of the adjusting mechanism showing portions of the same disaligned.

In the construction of lamps, particularly of the headlight type, it is customary to mount a reflector substantially rigidly in a casing, to adjustably mount a lamp bulb on the reflector and to mount a member on the casing for adjusting the said lamp bulb. More particularly there is usually formed an opening substantially centrally of the reflector and the lamp bulb is mounted in this opening for longitudinal or axial movement. There is further usually formed an opening in the lamp casing, in which opening there is mounted a member adapted to be manually actuated from the exterior of the lamp casing for effecting the adjustment of the lamp bulb.

The openings in the reflector and casing are usually formed centrally of each of these members and if extreme care is taken in the

manufacture of the lamp, these openings will be aligned when the reflector is mounted within the casing. In actual commercial production, however, it has been found, that while it is a comparatively simple matter to form the openings centrally of the reflector and casing, it is next to impossible to so perfectly form all the reflectors and all of the casings that when any reflector is assembled with any casing, the openings in the two will be aligned. Obviously, if when the reflector is mounted within the casing, the openings in the reflector and casing are not aligned, difficulty is experienced in installing the adjusting mechanism since, as brought out before, one portion of this adjusting mechanism is mounted in the opening in the casing and the other portion of the same is carried by or mounted in the opening in the reflector.

To overcome this difficulty and to facilitate the commercial production of the reflectors and lamp casings, without particular regard to the alignment of the openings in these members when the same are assembled, this invention contemplates the provision of means whereby compensation may be readily made for any variation in the alignment of the opening in the reflector with the opening in the casing.

Further in some forms of lamps, it is desirable, for the purpose of obtaining a certain reflection of the light rays from the lamp bulb, to mount the lamp bulb to one side of the center of the reflector. Obviously such a mounting of the lamp bulb positions the same to one side of the opening in the lamp casing, so that the same difficulty arises in the installation of adjusting mechanism in a lamp of this character as arises when the lamp bulb is out of alignment with the opening in the lamp casing by virtue of slight inaccuracies of manufacture. This invention will therefore also find particular utility in lamps of this character.

Referring now particularly to the drawings wherein like reference characters designate corresponding parts throughout all views of the same, there is disclosed a lamp, including the casing 10 and the reflector 11. The reflector 11 is mounted substantially

rigidly within the casing 10 as by engagement of the flange 12 with securing members, such as threaded members 13, carried by the rim 14 of the lamp casing.

In lamps of this character, it is customary to form an opening 15 substantially centrally of the reflector 11 and an opening 16 substantially centrally of the casing 10. The opening 15 is adapted to receive a lamp bulb and the opening 16 is adapted to receive an adjusting member, accessible from the outside of the lamp casing and connected to the lamp bulb, whereby actuation of the adjusting members adjusts the lamp bulb. As brought out before in the commercial production of lamps, difficulty is experienced in obtaining an accurate alignment of the opening 15 with the opening 16 and it therefore becomes necessary to provide some means whereby the adjusting member mounted in the opening 16 may adjust the lamp bulb mounted in the opening 15 regardless of this disalignment.

Referring now particularly to Figures 1 and 2 of the drawing, it will be noted that a bushing 17 is mounted in the opening 15 of the reflector 11. This bushing is adapted to slidably receive a lamp socket 18 provided with lateral projections 19 adapted to engage in slots 20 in the bushing 17.

The lamp socket 18 is adapted to receive a lamp bulb 21, which lamp bulb is movable with the socket 18 and is adapted to be adjusted by the mechanism hereinafter to be described.

Extending rearwardly from the bushing 17 and carried by the same is a frame 22 provided in its base with a slot 23 to receive a threaded member 24. The threaded member 24 is provided with a groove 25 which is engaged by the portions of the frame 22 bounding the slot 23, whereby the threaded member 24 is mounted for rotation and is fixed against longitudinal movement.

Rigidly secured to the socket 18 is an arm 26 bent as at 27 to form a portion adapted for threaded engagement with the threaded member 24. Obviously rotation of the threaded member 24 moves the arm 26 longitudinally to slide the lamp socket 18 and lamp bulb 21 longitudinally of the bushing 17.

The member 24 might be termed the driven member of the adjusting mechanism and for driving this driven member, there is provided a driving member 28 mounted for rotation in the opening 16 formed in the casing 10. The driving member 28 is provided with a head 29 adapted for engagement by a suitable adjusting tool and is counter-bored on its inner end to form the socket 30 slotted as at 31. Adapted for mounting in the socket 30 is a pin 32 provided with the ears 33 for engagement in the slots 31. Obviously rotation of the driving member 28

by the engagement of a suitable tool with the head 29 rotates the pin 32.

For effecting a driving connection between the pin 32, and the threaded member 24 and for compensating for variations in the alignment of the pin 32 with the member 24, there is provided a plate 35 having the diametrically arranged slots 36, 36', 36'' and 36'''.

As clearly illustrated these slots are arranged in pairs, the slots of each pair being diametrically opposite each other.

Carried by the threaded member 24 is a head 37 provided with the arms 38 bent at their ends for engagement in the diametrically opposite slots 36 and 36''. The arms 38 may be provided with heads 39 whereby they may be secured against disconnection from these slots.

The pin 32 is provided with a head 40 similar to the head 37 and with the arms 41 bent at their ends for engagement in the other pair of diametrically opposed slots 36' and 36'''.

The arms 41 are also provided with heads 42 whereby they may be maintained in engagement with their respective slots.

The arms 38 and 41 slidably engage their respective slots in the plate 35 to compensate for any variations in the alignment of the pin 32 with the threaded member 24. If desired a spring 43 may be sleeved on the driving member 28 for engagement with the casing 10 and the head 40 to urge the head 40 and pin 32 toward the plate 35.

As clearly illustrated in Figure 4 of the drawings, the heads 40 and 37 will readily adjust themselves with respect to the plate 35 to form a driving connection between the driving member 28 and threaded member 24 regardless of the position of the opening 15 with respect to the opening 16. Upon the rotation of the driving member 28, the arms 38 and 41 will slide in their respective slots to transmit this rotative movement to the member 24 and to compensate for any variation in the alignment of the member 24 with the member 28. The connection between the pin 32 and the member 24 permits movement of these elements relative to each other in two directions and permits adjustment of these members automatically upon the installation of the adjusting mechanism in the lamp.

While I have shown and described the invention as applied to lamps of the headlight type, it is obvious that the same may be applied to a lamp of any character, wherein it is desired to adjust the lamp bulb. It will be seen that the invention will eliminate the necessity of so forming the reflector and the casing as to cause the openings in the reflector and casing to be in accurate alignment and will thus permit the manufacture of lamps in commercial quantities without regard to absolute accuracy.

The present description and the drawings are submitted as one embodiment which the inventive idea may assume and are not to be construed as definitive of the limits to which the invention may be put. The right is therefore reserved to make such changes in the details of construction and arrangement of parts as will fall within the purview of the attached claims.

10. What I claim as my invention is:

1. In a headlight, in combination, a casing, a reflector within the said casing, the said reflector and casing each being provided with an aperture, a bushing in the aperture in the reflector, a lamp bulb axially movable in the said bushing, a frame carried by the bushing, a threaded member rotatably carried by the said frame, an arm carried by said lamp bulb and threadedly engaging the said threaded member, a headed element rotatably mounted in the aperture in the casing, the said headed element being counterbored to form a socket, a pin slidably but non-rotatably mounted in the said socket and means for connecting the free end of said pin with the free end of said threaded element and for compensating for variations in the alignment of the pin with the threaded element.

20. 2. In a headlight, in combination, a casing, a reflector within the said casing, the said reflector and casing each being provided with an aperture, a bushing in the aperture in the reflector, a lamp bulb axially movable in the said bushing, a frame carried by the bushing, a threaded member rotatably carried by the said frame, an arm carried by said lamp bulb, and threadedly engaging the said threaded member, a headed element rotatably mounted in the aperture in the casing, the said headed element being counterbored to form a socket, a pin slidably but non-rotatably mounted in the said socket and means for connecting the free end of said pin with the free end of said threaded element and for compensating for variations in the alignment of the pin with the threaded element, said means including a plate, a head on said pin slidably connected to said plate, and a head on said threaded element slidably connected to said plate for movement in a plane at right angles to the plane of movement of the head on the said pin.

30. 3. In a lamp, a casing, a reflector in said casing, a lamp bulb carried by said reflector, a rotatable driven member carried by said reflector for adjusting said lamp bulb, a driving member carried by said casing and separated from said driven member, and a driving connection between said driving and driven members permitting disalignment of said members.

40. 4. In a lamp, a casing, a reflector in said casing, a lamp bulb carried by said reflec-

tor, a driven member carried by said bulb and rotatable relative to said reflector, bulb and casing for adjusting said bulb relative to said reflector, a driving member carried by and rotatable relative to said casing, said driving member being spaced from said driven member, and a driving connection between said driving and driven members causing said members to rotate in unison but permitting disalignment of said members.

5. In a lamp bulb adjusting mechanism, a socket, an arm fixed to said socket, a rotatable member threadedly engaging said arm, a driving member for rotating said rotatable member, said driven and driving members being arranged substantially end to end with a space therebetween, and means connecting the driving member to the rotatable member for rotating the latter from the former and for compensating for variations in the alignment of the driving member with the rotatable member, said means including a coupling having parts connected to said driven and driving members and connected to each other.

6. In a lamp bulb adjusting mechanism, the combination with a lamp socket, of a threaded member connected to said socket for adjusting the same, a head on said threaded member, a coupling member slidably connected to said head, a pin slidably connected to said coupling member, and a headed element connected to said pin for rotating the same, said coupling member permitting movement of said pin relative to said threaded member to compensate for variations in the alignment of the axis of said pin with the axis of said threaded member.

7. In combination, a lamp casing, a reflector within the casing, a bushing rigid with the reflector, a socket slidable in the bushing, a lamp bulb mounted in the socket, a member rigid with the socket, and means for adjusting said socket and bulb relative to the bushing and reflector, including two rotary elements connected together so that they rotate in unison but are capable of two movements relative to each other, one of said elements constituting a driving means, and being accessible at the casing, and the other of said elements constituting a driven means and threadedly engaging the member rigid with the socket.

In testimony whereof I affix my signature.
FRANK L. BAMFORD.
